(57) **CLAIM**

The ornamental design for a container, as shown and described.

DESCRIPTION

FIG. 1 is a left side elevation of a container showing our new design;
FIG. 2 is a front elevation thereof;
FIG. 3 is a right side elevation thereof;
FIG. 4 is a rear elevation thereof;
FIG. 5 is a top plan view thereof;
FIG. 6 is a bottom plan view thereof;
FIG. 7 is a fragmentary cross sectional view in perspective of a lower portion of FIG. 1;
FIG. 8 is a fragmentary cross sectional view taken on line 8—8 in FIG. 1;
FIG. 9 is a fragmentary cross sectional view taken on line 9—9 in FIG. 1;
FIG. 10 is a fragmentary cross sectional view taken on line 10—10 in FIG. 4;
FIG. 11 is a left side elevation of a second embodiment of the container;
FIG. 12 is a front elevation of FIG. 11;
FIG. 13 is a right side elevation of FIG. 11;
FIG. 14 is a rear elevation of FIG. 11;
FIG. 15 is a top plan view of FIG. 11;
FIG. 16 is a bottom plan view of FIG. 11;
FIG. 17 is a fragmentary cross sectional view in perspective of a lower portion of FIG. 11;
FIG. 18 is a fragmentary cross sectional view taken on line 18—18 in FIG. 11
FIG. 19 is a fragmentary cross sectional view taken on line 19—19 in FIG. 11;
FIG. 20 is a fragmentary cross sectional view taken on line 20—20 in FIG. 14;

FIG. 21 is a fragmentary right side elevation of a third embodiment of the container, the portion of the third embodiment that is not shown is the same as the second embodiment;

FIG. 22 is a fragmentary rear elevation of FIG. 21;
FIG. 23 is a fragmentary left side elevation of FIG. 21;
FIG. 24 is a fragmentary right side elevation of a fourth embodiment of the container, the portion of the fourth embodiment that is not shown is the same as the second embodiment;

FIG. 25 is a fragmentary rear elevation of FIG. 24;
FIG. 26 is a fragmentary left side elevation of FIG. 24;
FIG. 27 is a fragmentary right side elevation of a fifth embodiment of the container, the portion of the fifth embodiment that is not shown is the same as the second embodiment;

FIG. 28 is a fragmentary rear elevation of FIG. 27;
FIG. 29 is a fragmentary left side elevation of FIG. 27;
FIG. 30 is a fragmentary right side elevation of a sixth embodiment of the container, the portion of the sixth embodiment that is not shown is the same as the second embodiment;

FIG. 31 is a fragmentary rear elevation of FIG. 30;
FIG. 32 is a fragmentary left side elevation of FIG. 30;
FIG. 33 is a fragmentary right side elevation of a seventh embodiment of the container, the portion of the seventh embodiment that is not shown is the same as the second embodiment;

FIG. 34 is a fragmentary rear elevation of FIG. 33;
FIG. 35 is a fragmentary left side elevation of FIG. 33;
FIG. 36 is a fragmentary right side elevation of an eighth embodiment of the container, the portion of the eighth embodiment that is not shown is the same as the second embodiment;

FIG. 37 is a fragmentary rear elevation of FIG. 36; and,
FIG. 38 is a fragmentary left side elevation of FIG. 36.
The fragmentary views in the drawings are shown on an enlarged scale.
